COMBINED COMMODE AND EXTENSION TABLE

Abe J. Gaines, Glencoe, Ill., assignor to Saginaw Furniture Shops, Inc., Chicago, Ill., a corporation of Michigan

Application March 29, 1954, Serial No. 29,754

Term of patent 14 years

(Cl. D33—13)

Fig. 3

Fig. 1

Fig. 2.

Figure 1 is a perspective view of a combined commode and extension table embodying my new design.

Fig. 2 is a perspective view thereof with the table element in extended position.

Fig. 3 is a fragmentary side elevation of the forward outer corner of the table element as shown in Fig. 2.

The dominant feature of my design for the particular combined commode and extension table disclosed resides in the uninterrupted surface of the flexible top of the extension table element as best illustrated in Fig. 2.

I claim:

The ornamental design for a combined commode and extension table, as shown and described.
